UNITED STATES PATENT OFFICE.

JUDSON H. MISKIMEN, OF GLENDIVE, MONTANA.

WRENCH.

1,369,459.

Specification of Letters Patent. Patented Feb. 22, 1921.

Application filed February 2, 1920. Serial No. 355,662.

To all whom it may concern:

Be it known that I, JUDSON H. MISKIMEN, a citizen of the United States, residing at Glendive, in the county of Dawson and State of Montana, have invented certain new and useful Improvements in Wrenches; and I do hereby declare the following to be a full, clear, and exact description of the invention, such as will enable others skilled in the art to which it appertains to make and use the same.

My invention has for its object to provide an improved wrench that is readily adjustable to nuts of different sizes, and, to such ends, generally stated, the invention consists of the novel devices and combinations of devices hereinafter described and defined in the claim.

The wrench, in its preferred form, is illustrated in the accompanying drawings, wherein like characters indicate like parts throughout the several views.

Referring to the drawings:—

Figure 1 is a plan view of the wrench, certain parts being removed;

Fig. 2 is a perspective view of the complete wrench; and

Fig. 3 is a perspective view showing one of the movable jaws of the wrench, the elements of the jaws being separated.

In the preferred form of the wrench, a suitable hand-piece is provided at both ends with fixed and adjustable jaws of the same construction, at both ends, except that the jaws at the one end are preferably larger than those at the other end. A description of the jaw construction at the one end will suffice for that of both of the ends.

The handle or lever 4 is preferably a flat steel bar, with flat head portions 5 at its ends. The head 5 is formed with an integral or fixed nut-engaging jaw 6, and, at a right angle to the nut-engaging edge of said jaw, said head has a front edge 7, formed with longitudinally spaced ratchet teeth 8. The head 6, in its bottom portion, is formed with a slot 9 that is nearly parallel to the edge 7, and, on its front edge, is formed with longitudinally spaced notches 10.

For coöperation with the fixed jaw 6,

there is a movable or adjustable jaw and this jaw is a bifurcated structure preferably made up of flat cheek plates 11, and an interposed relatively short spacing plate 12, said elements 11 and 12 being rigidly connected by rivets 13. The spaced portions of the plates 11 embrace or straddle the head 5 and are provided with a rigidly secured pin 14 that works through the slot 9 and is engageable with any one of the lock notches 10 thereof. The spacing plate 12, at its inner edge, has a ratchet-like tooth 15 that is engageable with any one of the ratchet teeth 8.

When the pin 14 is engaged with one of the notches 10, the tooth 15 will be engaged with one of the ratchet teeth 8 and the nut-engaging edges of the jaws 6 and 11—12 will be parallel, or, as shown by full lines in the drawings. To adjust the movable jaw toward or from the fixed jaw, it is necessary first to rock the former to a position indicated by dotted lines at the left in Fig. 1, and then the said jaw, thus rocked, may be slid either toward or from the fixed jaw and may thereafter be relocked to the head 6 in any of its several possible adjustments. The above noted adjustments may be quickly accomplished and the movable jaw is very rigidly locked in respect to the fixed jaw.

What I claim is:—

A wrench comprising a handle having a flat head with a fixed jaw, said head having a notched slot and a notched front edge, in combination with an adjustable jaw made up of laterally spaced cheek plates and an interposed spacer plate rigidly connected together, said spacer plate at its inner edge having a tooth for engagement with the notched front edge of said head, and the spaced portions of said cheek plates embracing the said wrench head and having a transverse pin that works in the slot of said head and is engageable with the notches thereof.

In testimony whereof I affix my signature in presence of a witness.

JUDSON H. MISKIMEN.

Witness:

HARRY D. KILGORE.
